S. LESLIE, OF SHARON, PENNSYLVANIA.

DRAINAGE MEANS FOR WATER-SUPPLY SYSTEMS.

SPECIFICATION forming part of Letters Patent No. 746,115, dated December 8, 1903.

Application filed February 15, 1901. Serial No. 47,400. (No model.)

To all whom it may concern:

Be it known that I, ROBERT F. LINDSAY, a citizen of the United States, residing at Greenville, in the county of Greenville and State of South Carolina, have invented certain new and useful Improvements in Drainage Means for Water-Supply Systems; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to that class of house water-supply systems embracing automatically-operated means for draining the service-pipe of the system when the temperature has dropped to a predetermined point, so as thereby to prevent freezing of the water in said pipe; and the invention consists in certain novel combinations of elements and in certain peculiarities in the detail construction of parts embodied in the system, substantially as hereinafter described, and particularly pointed out in the subjoined claims.

A principal object of the present invention is to provide a system which will not only include means for automatically shutting off the supply of water to the service-pipe and draining said pipe when the temperature falls below a predetermined point, but will also include means by which the valves of the system may be temporarily restored to their normal positions, so as to enable water to be drawn from the service-pipe for use when the temperature is below that at which the cut-off and drain is set to operate, and will, furthermore, include means by which the flushing-tank of a water-closet embraced in the system will be drained of its contents at the same time said service-pipe is drained.

Further objects of the invention are to improve the construction of the parts entering into the system.

These objects are accomplished by the constructions shown in the accompanying drawings, wherein like numerals of reference designate the same parts in the several figures, and in which—

Figure 1 is a view illustrating the entire system, showing the principal parts in section and the parts thereof in the positions they occupy when the supply of water to the service-pipe is shut off and said pipe and the flush-tank are being drained. Fig. 2 is an enlarged side view of the end of the thermostat, showing the rod thereof raised. Fig. 3 is a sectional view of the parts shown in Fig. 2. Fig. 4 is a vertical section through the cut-off and drain with the parts thereof in the positions they occupy when the system is in service. Fig. 5 is a vertical sectional view of the cylinder and plunger used for opening the drain-pipe of the closet flush-tank, showing the plunger in the position it occupies when said pipe is closed. Fig. 6 is a sectional view of a modified form of device for draining said flush-tank, showing the position of the plunger when the pipe is being drained thereby. Fig. 7 is a sectional view of a modified form of cut-off and drain valve with the parts shown in the position they occupy when the supply of water to the service-pipe is open and the drain-port from said pipe cut off. Fig. 8 is a sectional view of a further modified form of cut-off and drain valve, showing the position of the parts when the drain-port is open and the communication between the supply and service pipes is cut off. Fig. 9 is a sectional view of the form shown in Fig. 8, but shows the positions of the parts when the drain-port is closed and communication between the supply and service pipes is open. Fig. 10 is a detail view of the faucet-valve, which admits air to the service-pipe to assist in draining the same.

Referring now to the drawings, there is shown a water-supply system including a service-pipe 5, with which is connected a water-supply pipe 6 through the medium of an automatic cut-off and drain apparatus (shown generally at 7) and which is connected with the supply-pipe 6 by means of the usual pipe connections. The cut-off and drain mechanism is operated to permit its function through the medium of a thermostat 8, which is connected therewith, and the system also includes a means (indicated generally at 9) which is in communication with the service-

pipe 5 and by which the valve 11 in the flush-tank 12 is raised from its seat to drain said tank when the service-pipe is being drained, as hereinafter described.

5 In the construction of cut-off and drain shown in Fig. 4 there is embraced a cylinder 13, in which is located a piston 14, having a stem or rod 15, which extends downward through an opening 16 in the lower end of 10 said cylinder and into a drainage-chamber 17, from which the service-pipe 5 leads. Said opening 16 is of greater diameter than the rod 15, though of lesser diameter than the piston, so that water may flow from the cylinder 15 into the drainage-chamber. A valve 18 is carried by said piston-rod and is located in said drainage-chamber, and the lower end of said rod is formed to provide a valve 19, which is located adjacent to a port 20 in said 20 drainage-chamber. It will thus be seen that when the piston is raised it will cause the opening 16 to be closed by the valve 18 and the drainage-port 20 to be opened by the valve 19 and that when said piston is lowered 25 the former opening will be uncovered and the drainage-port closed. The action of the piston is controlled as follows: The supply-pipe 6 opens into a supply-chamber 21, which communicates with the portion of the cylinder 13 30 below the piston 14 through an opening 22, formed in the side of the lower end of said cylinder, and communicates with the portion of said cylinder above said piston through an opening 23, a valve-chamber 24, and an opening 25. Said valve-chamber 24 has valve-seats 26 and 27 at its top and bottom, respectively, and said opening 25 is formed in the upper portion of the cylinder 13 and is located between the plane of said valve-seats. 35 40 Rising from said valve-chamber is a casing 28, which has a vent-port 29, and arranged in said valve-chamber is a spherical or other suitable valve 30, which is adapted to alternately engage said valve-seats 26 and 27. Said valve is carried by a stem 31, which is encircled by a helical spring 32, which is confined between the top of the casing 28 and an abutment 33, fixed on said stem. Normally the valve is held elevated to its seat 27 by the 45 means hereinafter described, and when relieved of the upholding force it is pressed down to its seat 26 by the spring 32.

When the valve is in its normal position, (shown in Fig. 4,) the water will flow from 50 the supply-pipe 6 into the cylinder 13 through the ports 22 and 25 in the latter, and there will be a preponderance of downward pressure imposed thereby which will act to hold the port 17 open and the drainage-port 20 closed. When, however, the valve 30 is lowered to its seat 26, the supply of water to the upper portion of the piston-chamber 13 is immediately cut off, and said upper portion is thrown into communication with the atmosphere through its port 25, the now open port 27' contiguous to the valve-seat 27, and the vent-port 29. A preponderance of pressure

will thus be imposed beneath the piston 14, which will cause the same and the valves carried thereby to be lifted, thereby closing 70 the port 17 and shutting off further supply of water to the service-pipe 5 and at the same time lifting the drainage-valve 19 and permitting the contents of the service-pipe to be drained therefrom through the drainage-port 75 20. The water in the portion of the cylinder 13 above the piston 14 finds its way to the outside of the device while said piston is being raised through the openings 25, 27', and 29, above referred to. 80

It is desirable to admit air to the service-pipe while the latter is being drained to facilitate drainage thereof. A very desirable means for this purpose, which, however, is not claimed *per se* herein, is shown in Fig. 1. 85 In said figure the faucet 34 of the kitchen-sink 35 is so constructed that it may be used for the ordinary purposes of such a faucet and embodies means for automatically admitting air to said service-pipe, as stated. The faucet comprises a common form of casing 36, having the horizontally-disposed diaphragm 37, which divides the body of the faucet into two chambers 38 and 38', and leading into the chamber 38 is a threaded valve-stem 40, having engagement with the threads of the opening 41 in the upper wall of the chamber. The stem 40 has a transverse handle 41' of usual form at its upper end, and at its lower end and within the chamber 38 is a disk 42, secured thereto in any suitable manner. Said disk is adapted to directly engage the valve 43 of the faucet to press it into its closed position in the valve-seat 44 to control the opening 45 in the diaphragm 37. The valve 43 comprises an inverted frusto-conical body having a radially-extending flange 46 at its upper major end and of such diameter as to rest upon the valve-seat 44 or upon the diaphragm adjacent the opening 45, said flange 46 having an annular groove in its under face in which is seated a washer 47 to insure a water-tight joint. The lateral dimensions of the valve are such that when lowered it will fit snugly in the opening 45, and when it is raised 95 from its seat there will be presented a space sufficient to allow a free flow of water to the chamber 39. A passage 48 is formed vertically through the valve 43, and the lower end of said passage is increased in diameter to form a valve-chamber 49, in which is disposed a ball-valve 50, which in rising closes the passage 48, the ball being held against downward displacement from the chamber by a pin 51. Thus when pressure is in the pipe 6 the ball will be held in its closed position, and when pressure is relieved, as by operation of the cut-off and drain above described, the ball will drop and will permit air to enter the service-pipe through the passage 48 in the valve. In order that there may be a free flow of air to the passage 48 when the disk 42 is upon the upper face of the valve 43, said upper face is formed with a series of concentric grooves 52, con-

nected by radial grooves 53, which extend through the outer edge of the valve. It will of course be understood that the valve is closed by downward movement of the stem 5 40 and is opened by water-pressure exerted against its under side when said stem is raised.

In Fig. 1 of the drawings the system is also shown as including a water-closet 55, having 10 a flush-tank 56, to any suitable place in which leads the service - pipe 5. Suitable means will, of course, preferably be provided for preventing the flushing-tank from becoming 15 too full of water; but as many of such means are well known in the art it is not deemed necessary to show or describe any of them herein. Leading from the flushing-tank to the closet-bowl is the flushing-pipe 57. The 20 valve 11 of the flushing-tank is opened and closed manually—for instance, by means of a lever 58, such as usually employed for this purpose—and connected with this lever is the means 9, hereinabove referred to, for opening 25 said valve automatically, and thus relieving the tank of its contents simultaneously with the draining of the service-pipe 5. Said device 9 comprises a cylinder 59, which is connected with the service-pipe in advance of the 30 flushing-tank and contiguous to the latter and provided with a piston 60 therein, having its 35 rod 61 extended through the top of the cylinder and connected with the lever 58 by a chain 62 or other suitable means. A helical spring 63 encircles the piston-rod and rests with its 40 ends against the piston and the upper end of the cylinder, respectively, and tends to hold the piston in a lowered position. The connection of the cylinder with the service-pipe is 45 below this piston, and the water-pressure on said piston holds the piston against the tendency of the spring, the result being that the chain 62 is held slack and does not prevent manual operation of the lever 58 when the system is in service. When, however, the 50 pressure in said service-pipe is relieved, the piston moves under the influence of its spring and drawing upon the chain 62 operates through said lever to open the valve 11, and thus drains the tank through the pipe 57.

50 A very advantageous means for automatically controlling the action of the valve 30 in the cut-off and drain will now be described. Said means includes as a principal element a thermostat 8, secured at a suitable place 55 and embracing a thermostatic rod of any suitable construction. Arranged contiguous to the free end of said thermostatic rod and suitably supported in a position preferably perpendicular thereto is a sleeve 65, through 60 which extends a longitudinally-movable rod 66, having its upper end provided with a handle 67 for raising it manually and having its lower end connected, preferably by the means hereinafter stated, with the stem 31 of said valve 30, so that when said rod is in its elevated position said valve will be held to its seat 27, and when said rod is lowered the

spring 32, encircling said valve, will become effective to force and hold said valve to its seat 26 against the pressure of inflowing water from the supply-pipe 6. The rod 66 is held in its raised position by a catch 68, having one of its ends secured to a fixed support, as 69, and its other end, 70, bent and extended through a perforation 71 in the sleeve 65 and adapted to engage a shoulder or recess 72 in the rod 66. A spring 73, connected with said catch, holds the latter yieldingly in position to engage said shoulder or recess 72 when the same is brought into registry with the end 70 of the catch by the raising of the rod, and said catch is operated automatically to release the rod and permit it to drop by the contraction of the thermostat-rod, the free end of which embraces said rod, as shown 85 best in Fig. 3. The means preferably employed for connecting said rod 66 with the valve-rod 31 comprises a lever 74 of the bent form shown arranged in an inclined position and having one end pivoted to a suitable bifurcated support or yoke, as 75, mounted on top of the casing 28 and pivotally attached between its ends to the upper end of the valve-rod 31, and a chain 76 or other suitable connecting means extending from the lower end 90 of said rod 66 and attached to the lever 74 at a place in the latter between the valve-rod 31 and its free end.

From the above description of the construction of the system the operation thereof will 100 readily be understood to be as follows: Under normal conditions—that is to say, when the temperature is high enough to render freezing of the water in the service-pipe improbable—the valves of the cut-off and drain 105 will be in the position shown in Fig. 4, so that water will be permitted to flow freely through said service-pipe. The plunger 60 in the cylinder 59 will be held elevated by the pressure of water exerted against the under side of the same, thereby holding the chain 62 slack and permitting the bowl to be flushed by manual depression of the free end of the lever 58. The ball-valve 50 in the faucet-valve 43 will be held to its seat by the 110 water-pressure in the service-pipe, so as to exclude air from said pipe, and the rod 66 will be held elevated to retain the valve 30 against its seat 27. When the temperature drops to that at which the thermostat is set 115 to operate the cut-off and drain, its contraction withdraws the catch 68 from its engagement with the rod 66, permitting said valve 30 to be forced downward upon its seat 26, thus excluding water from the upper portion of 120 the cylinder 13 and causing a preponderance of pressure to be exerted against the underside of the piston 14, thereby raising the cut-off valve to its seat and the drain-valve from its seat. The pressure in the service-pipe is now 125 cut off and the drain - port in the latter is opened, and consequently said ball-valve 50 drops from its seat, allowing air to flow into 13 the service-pipe and causing the latter rapidly

to be drained of its contents. Consequential also upon the cessation of the pressure in the service-pipe the spring 63 becomes operative to force the piston 60 downward, thus taking up 5 the slack in the chain 62 and pulling downward the free end of the lever 58, thereby raising the valve 11 and draining the flushing-tank. The parts are now in the position shown in Fig. 1. If during such period of 10 cold weather the use of water is desired, it is only necessary with the means thus far described to raise the rod 66 and hold it elevated until the required quantity of water has been drawn, the raising of said rod ob- 15 viously elevating the valve 30 and causing the water-pressure so to actuate the piston as to throw the supply-pipe into communication with the service-pipe and close the drain from said pipe. If said rod 66 be raised at a time 20 when the thermostatic rod is expanded until the recess or shoulder 72 in said rod registers with the free end of the catch 68, the latter will immediately snap into engagement with said recess or shoulder, and thereby hold said 25 rod elevated until the temperature again drops to that at which the thermostat is set to shut off the supply of water to the service-pipe and open the drain-port from the latter.

In order that water may be drawn from the 30 service-pipe or flush-tank temporarily when the system has been thrown out of service by the influence of cold weather without going to the thermostat for this purpose, a pivoted lever 77 may be situated at a suitable 35 place—for instance, in the water-closet, adjacent to the handle of the chain 58', by which the flushing-lever 58 is actuated manually—said lever 77 being connected, as by means of a chain 78 passing over a direction-pulley 40 79, with the downwardly-bent extremity 80 of said lever 74, so that when the free end of said lever 77 is depressed from the position in which it is shown in Fig. 1 it will cause the valve-rod 31 to be elevated and the valve 30 45 to be raised to its seat 27.

This invention is not restricted to the specific construction of parts herein shown and described, as various modifications therein may be made without departing from the 50 spirit of the invention. A few of the many modifications which are within the scope of the invention are shown in the accompanying drawings and will now be described.

In the form of device for draining the flush- 55 ing-tank shown in Fig. 5 there is no provision for adjusting the tension of the spring which acts in opposition to the pressure of the water in the service-pipe. A tension-adjusting means for said spring is obviously ad- 60 vantageous, and a suitable form thereof is shown in Fig. 6, wherein the cylinder is shown as provided with a cap 159, threaded thereupon and having a threaded bore into which screws the lower end of an externally- 65 threaded sleeve 160, that bears upon the upper end of the spring 163 and is adjustable through said cap to regulate the tension of the

spring. The piston-rod 161 extends through said sleeve, as shown. A lock-nut 162 may be provided for fixing the sleeve 160 in adjust- 70 ed position.

Fig. 7 illustrates a form of double valve which may be substituted for the cut-off and drain valves 18 and 19 shown in Fig. 4, and said double valve consists of two cones or 75 cone-surfaces, of which the upper, 118, controls the opening 117, through which the cylinder 113 (in which the piston connected with said valves is located) has communication with the drainage-chamber 116, and the lower 80 conical surface 119 of said valve controls the drainage-port 120 in said chamber.

In Figs. 8 and 9 there is shown a modified construction wherein a trip-valve 118^a is provided for closing the drain-port in lieu of the 85 valves shown in the other forms of the device, and the drainage-chamber is shown as closed at the bottom by a cap 125, having a lateral port 126. The downwardly-extending stem 16^b of the valve 16^a extends into a tubular projection 118^b from said trip-valve, and said projection has an elongated slot 118^c in its wall into which a pin or pins 118^d extend from said stem 16^b. A seat 118^e is provided for the valve—for example, near the upper 95 end of the cap 125, as shown. In the normal position of the parts (shown in Fig. 9) the valve 30^a will be upon the seat 27^a and water will be permitted to flow from the supply-pipe through the openings 25^a and 22^a above 100 and below the plane of the piston-head, and a preponderance of downward pressure will exist which will hold the valve 16^a from its seat and the valve 118^a to its seat, whereby the service-pipe will be in communication 105 with the supply-pipe and the drain-port will be closed. When, however, the valve 30^a is lowered to its seat 26^a, in which position it is shown in Fig. 8, the supply of water through the upper port 25^a will be cut off, thus shifting the balance of pressure and causing it to 110 preponderate in an upward direction, raising the valve 16^a to its seat, and when the pin 118^d has reached the upper end of the slot 118^c causing it to lift the valve 118^a from 115 its seat, thus opening the drain at about the moment the communication between the supply and service pipes is cut off. At the moment the valve 30^a is again raised to its seat 27^a the preponderance of pressure is again 120 shifted and the drain-port is quickly closed by the valve 118^a, which may reach its seat before the valve 16^a has reached its lower limit of travel.

It will be observed that the ports 22 and 25 125 are in direct communication with the supply passage or chamber 21 and that the cylinder 13 has communication with said supply chamber or passage only through said ports and also that the cut-off and drainage valves 130 are both located and operate wholly within the drainage-chamber. By this particular construction and arrangement of parts the device is of the simplest construction and

the valves and piston caused to respond most readily to the changes in pressure above noted.

Having thus described the invention, what I believe to be new, and desire to secure by Letters Patent, is—

1. In a water-supply system, the combination with a water-containing receptacle, having a valved exit-opening, means for supplying said receptacle with water, and means for draining said supply means, of means controlled by the pressure in the supply means for draining said receptacle automatically, comprehending essentially devices operatively connected with the valve of said receptacle and so related to the pressure in the supply means as to open said valve when said pressure is reduced or ceases.

2. In a water-supply system, the combination with a water-containing receptacle, having a valved exit-opening, means for supplying said receptacle with water, comprising a supply-pipe, a service-pipe having communication with said supply-pipe and receptacle, and a combined cut-off and drain valve in said service-pipe having temperature-controlled means for operating it automatically, of means controlled by the pressure in said service-pipe for draining said receptacle automatically, comprehending essentially a device operatively connected with the valve of said receptacle and so related to the pressure in the service-pipe as to open said valve when said pressure is reduced or ceases.

3. The combination with a water-closet flushing-tank and a valved flushing-pipe leading therefrom, of means for supplying said tank with water, and devices exposed to the pressure of water in the supply means and connected with the valve in said flushing-pipe so as to open said valve when the pressure in the supply means is reduced or ceases.

4. The combination with a water-closet flushing-tank, a flushing-pipe leading therefrom, and a valve for said pipe, of means for supplying said tank with water, a device exposed to the pressure in the supply means and connected with said valve so as to open the same automatically when said pressure is reduced or ceases, and means for opening said valve by hand when there is pressure in the supply means.

5. In a water-supply system, the combination with a service-pipe, means operable to cut off supply of water to said pipe and open a drain-port from the same, a closet flushing-tank in communication with said pipe, and a flushing-pipe leading from said tank, of a valve controlling the opening to said flushing-pipe, devices connected with said valve and operable manually to raise and lower the same, and means connected with said devices and controlled by reduction of pressure in the service-pipe to actuate said devices and open said valve automatically.

6. In a water-supply system, the combination with a service-pipe, devices operable to

cut off supply to said pipe and open a drain-port from the same, a closet flushing-tank in communication with said pipe and a flushing-pipe leading from said tank, of a valve controlling the opening to said pipe, a pivoted lever connected with said valve and operable manually to raise and lower the same, a reciprocating device controlled in its movement by pressure in the service-pipe, and a connecting device between said lever and reciprocating device, said connecting device being adapted to permit manual operation of the lever when the reciprocating device is at one position of its travel and to actuate said lever during the travel of said reciprocating device in one direction, to open the valve automatically when the service-pressure is reduced or ceases.

7. In a water-supply system, the combination with a service-pipe, and devices operable to cut off supply of water to said pipe and open a drain-port therefrom, of a water-containing tank having a valved opening, and a piston controlled by service-pressure and connected with the valve of said opening so as to open the same when said pressure is reduced or ceases.

8. In a water-supply system, the combination with a service-pipe, and devices operable to cut off supply of water to said pipe and open a drain-port therefrom, of a water-containing tank having a valved opening, a piston upheld by service-pressure and connected with the valve of said opening, and a spring engaging said piston and adapted to depress the same and thereby open said valve when said pressure is reduced or ceases.

9. In a water-supply system, the combination with a service-pipe, means operable to cut off supply of water to said pipe and open a drain-port from the same, a closet flushing-tank in communication with said pipe, and a flushing-pipe leading from said tank, of a valve controlling the opening to said flushing-pipe, a manually-operable lever connected with said valve, and a piston actuated, when the pressure in the service-pipe is reduced or ceases, to operate said lever and raise said valve automatically.

10. In a water-supply system, the combination with a service-pipe, means operable to cut off supply of water to said pipe and open a drain therefrom, a closet flushing-tank in communication with said pipe, and a flushing-pipe leading from said tank, of a valve controlling the opening to said flushing-pipe, a manually-operable lever connected with said valve, a piston exposed to service-pressure and upheld thereby, a spring pressing said piston in opposition to said pressure, and a flexible connection between said piston and lever.

11. In a water-supply system, the combination with service and supply pipes, of a combined cut-off and drain having its casing connected with said pipes, a thermostat connected with the cut-off and drain for operating the

same, a tank, a drain from the tank, a valve for closing the drain, said valve being adapted to lie normally in its closed position, a piston sustained by service-pipe pressure and having connection with the tank - valve, and means for moving the piston to open the tank-valve when the pressure is reduced.

12. In a water-supply system, the combination with a service-pipe and a supply-pipe, of a combined cut-off and drain valve comprising a casing disposed in connection with said pipes, a piston in said casing, said supply-pipe having normally communication with the casing at both sides of the piston, and means for cutting off the supply-pipe pressure from one side of the piston, to move the piston to close the cut-off and open the drain.

13. A combined cut-off and drain, comprising a casing including a cylinder and a drainage-chamber having a communicating opening, a piston in the cylinder, valves disposed in the drainage-chamber and connected with the piston for movement thereby to open and close the drainage-chamber and the opening between it and the cylinder, a supply-chamber adapted for connection of a supply-pipe therewith, said supply-chamber having openings communicating it normally with the cylinder at both sides of the piston therein, and a valve constructed and arranged for cutting off the water-supply from the supply-chamber to the cylinder at the upper side of the piston, to actuate the piston, to open the drain-valve and close the communication between the cylinder and drain-chamber.

14. A combined cut-off and drain, comprising a casing including a cylinder and a drainage-chamber, said drainage-chamber having a drain-port and said cylinder having an opening through which it communicates with said drain-chamber, a piston in said cylinder, drain and cut-off valves for said port and opening respectively, said valves being carried by the piston and both located in the drainage-chamber, whereby the raising of said piston opens the drain-port and closes said communicating opening and vice versa, a supply-chamber adapted for direct communication with the supply-pipe, two lateral ports located in the cylinder-wall above and below said piston and both having direct communication with said supply-chamber and said chamber being constantly in communication with said cylinder through the lower of said ports, and a valve which controls the admission of water from the supply-chamber to the upper of said ports, whereby when both ports are in communication with the supply-chamber the water will flow directly from the supply-pipe to the portions of the cylinder both above and below the piston and will hold the cut-off valve open and the drain-valve closed, and when water is admitted to the lower side only of said piston the latter will be raised to cut off communication to the service-port and open the drain-port.

15. A cut-off and drain comprising a cylin-

der and a drainage-chamber having a communicating opening, said drainage-chamber having a drain-port, a piston in the cylinder 70 and having a rod passed into the drainage-chamber to close the drain-opening, a valve upon the rod within the drain-chamber disposed to close the opening between the cylinder and drainage-chamber when the drain 75 is opened and to move against pressure from the cylinder, a supply-chamber communicating normally with the cylinder at both sides of the piston, and means for alternately opening and venting the cylinder at the opposite 80 side of the piston from the communication with the drain-chamber, to reciprocate the piston and alternately operate the valves carried thereby.

16. A device of the class described, comprising a casing including a cylinder, a piston in the cylinder, a drain-chamber communicating with the cylinder and having a drain-opening, a rod for the piston extending into the drain-chamber and adapted to open and 90 close the drain-opening as the piston is reciprocated, a valve upon the piston-rod and lying within the drain-chamber for movement under the influence of supply-pressure to open and close communication between 95 the chamber and cylinder, a supply-chamber connected with the cylinder below the piston and through the cylinder with the drain-chamber, a valved chamber having spaced valve-seats, an opening between the valve-chamber and cylinder and located between the valve-seats of the chamber, said valve-chamber having communication through one of the seats with the supply-chamber and through the other seat with a vent, and a 100 valve for engagement with the seats alternately to shift the balance of pressure to opposite sides of the piston to move it and the valves operated thereby.

17. A water-supply system, comprising a 110 service-pipe, a supply-pipe, a cut-off and drain connecting the pipes, a thermostat connected with the cut-off and drain for operating them, a faucet connected with the supply-pipe and having a valved air-inlet, a tank, 115 a drain for the tank, a valve for the drain, means for opening the valve and means operated by service-pipe pressure for holding the operating means normally inoperative.

18. In a water-supply system, the combination with service and supply pipes, cut-off and drain valves for controlling the communication of the supply-pipe with the service-pipe and the drain from the latter, and a means operated by a preponderance of pressure on the one or the other of its sides for operating said valves, of means for shifting said pressure automatically, including a valve which controls access of the pressure medium, a thermostat, and connections between said thermostat and valve, said connections including a releasing means which is actuated by said thermostat to free the valve from the influence of the thermostat upon a predetermined

change in temperature, substantially as described.

19. In a water-supply system, the combination with the service and supply pipes, cut-off and drain valves for controlling the communication of the supply-pipe with the service-pipe and opening and closing the drain from the latter, a means operated under the influence of a preponderance of pressure on one or the other of its sides for operating said valves, of devices for controlling said preponderance of pressure, said devices including a valve which in one position causes the preponderance of pressure to be below said means and when in the other position causes said preponderance to be above said means, a thermostat, a rod connected with said valve and held by the action of the thermostat when the latter is expanded and released therefrom when the thermostat is contracted, and means for moving said valve from one to the other of its positions when said rod is released.

20. In a water-supply system, the combination with the service and supply pipes, cut-off and drain valves for controlling the communication of the supply-pipe with the service-pipe and opening and closing the drain from the latter, and a means operated under the influence of a preponderance of pressure on one or the other of its sides for operating said valves, of devices for controlling said preponderance of pressure, said devices including a valve which in one position causes the preponderance of pressure to be below said means and in the other of its positions causes said preponderance to be above said means, a valve-rod, a pivoted lever pivotally attached to said rod, a thermostat, a catch controlled by said thermostat, a rod connected with said lever and held by said catch when the thermostat is expanded so as thereby to hold the valve in one of its positions, and means for forcing the valve to the other of its positions when the contraction of said thermostat has released said rod.

21. The combination with cut-off and drain valves of a water-supply system, of a means for controlling the action of said cut-off and drain valves, said controlling means including a valve, a device operable manually to adjust said valve to one of its positions, and a thermostat which when expanded will hold said device and thereby the valve in said adjusted position.

22. An automatic cut-off and drain apparatus, comprising a casing including a cylinder, a drain-chamber communicating with the cylinder and having a drain-opening, a piston in said cylinder, cut-off and drain valves connected with said piston, a supply-chamber connected with the cylinder below the piston, a valved chamber having spaced valved seats, said chamber having communication with said cylinder above the piston by means of an opening located in a plane between said seats, and also having communication through one of its seats with said supply-chamber and

through its other seat with a vent, a valve for engagement with the seats alternately to shift the balance of pressure to opposite sides of 70 said piston, a spring tending to press said valve toward one of its seats, and devices for holding said valve against the action of said spring and automatically releasing the valve when the same should be adjusted, comprising a pivoted lever pivotally connected with said valve, a thermostat, a catch controlled by said thermostat, and an adjustable device connected with said lever and adapted to said catch, so as to be held thereby in one position 80 when the thermostat is expanded and released therefrom when the thermostat is contracted.

23. In a cut-off and drain mechanism for water-supply systems, the combination with 85 supply and service pipes, a casing disposed in connection with said pipes, and valvular mechanism for controlling cut-off and drain ports, said valvular mechanism being actuatable under the influence of preponderance of pressure on one or the other side, of mechanism for controlling access of water to said casing so as to thereby control said preponderance of pressure, including a valve, a thermostat and means by which the valve is freed from 95 the thermostat under the influence of a predetermined change in temperature on the latter.

24. In a cut-off and drain mechanism for water-supply systems, the combination with 100 supply and service pipes, a casing disposed in connection with said pipes and valvular mechanism in said casing for controlling cut-off and drain ports, said valvular mechanism being actuatable by a preponderance of pressure on one or the other side, of mechanism 105 for controlling access of water to said casing so as to thereby control said preponderance of pressure, including a valve, a connecting means by which the valve may be adjusted manually, and a thermostat having a catch to engage said connecting means and thereby hold and release said valve.

25. In a cut-off and drain mechanism for water-supply systems, the combination with 115 supply and service pipes, a casing disposed in connection with said pipes and valvular mechanism in said casing for controlling cut-off and drain ports, said valvular mechanism being actuatable by a preponderance of pressure on one or the other side, of mechanism 120 for controlling access of water to said casing so as to thereby control said preponderance of pressure, including a reciprocating valve, a spring pressing the same in one direction, a connecting means, and a thermostat having 125 a catch to engage said connecting means and hold the valve in opposition to said spring, said catch being freed from the connecting means by the action of said thermostat to thereby permit said spring to adjust the valve. 130

26. In a cut-off and drain mechanism for water-supply systems, the combination with supply and service pipes, a casing disposed in connection with said pipes and valvular

mechanism in said casing for controlling cut-off and drain ports, said valvular mechanism being actuatable by a preponderance of pressure on one or the other side, of mechanism 5 for controlling access of water to said casing so as to thereby control said preponderance of pressure, including a reciprocatory valve, a spring tending to press said valve in one direction, and thermostatic means acting in 10 opposition to said spring and embracing a thermostatic rod having a catch at one end, a sleeve contiguous to said catch, and a connection between said valve and rod, including a longitudinally-movable rod within said 15 sleeve, confined in its movements thereby and adapted to said catch so as to be held thereby when the thermostatic rod is expanded and released therefrom when the same is contracted, and a handle by which said rod may be 20 raised manually when it is released from said catch.

27. In a cut-off and drain mechanism for water-supply systems, the combination with supply and service pipes, a casing disposed 25 in connection with said pipes, and valvular mechanism in said casing for controlling cut-off and drain ports, said valvular mechanism being actuatable by a preponderance of pressure on one or the other side, of valve mechanism 30 for controlling access of water to said casing so as to thereby control said preponderance of pressure, comprising a reciprocatory valve, a pivoted lever pivoted to the stem of said valve, a spring tending to press said 35 valve in one direction, a thermostat having a catch, a longitudinally-movable rod adapted to said catch so as to be held thereby and hold the valve against the action of said spring when the thermostat is expanded, a flexible 40 connection between said pivoted lever and rod, a separate lever, and a flexible connection between the latter lever and said pivoted lever.

28. The combination with the cut-off and 45 drain valves of a water-supply system, of a means for controlling the action of said valves, said controlling means including a valve, a

device connected therewith and adjustable manually to adjust said valve to one of its positions, a thermostat which holds said device and valve normally in said adjusted position, and automatically releases the same under the influence of temperature, and a supplemental device for throwing the system into service temporarily when the first-mentioned 50 device is released from said thermostat, said supplemental device also being connected with the valve of the controlling means, and the connections of said devices with said valve being such that neither of said devices interferes with the manual adjustment of the other.

29. In a water-supply system, the combination with the service and supply pipes, cut-off and drain valves for controlling the communication of the supply-pipe with the service-pipe and opening and closing the drain from the latter, and means operated under the influence of a preponderance of pressure 65 on one or the other of its sides for operating said valves, of devices for controlling said preponderance of pressure, said devices including a valve which in one position causes the preponderance of pressure to be on one side of said means and in the other of its positions causes said preponderance to be on the other side of said means, a valve-rod, a lever pivoted at one end and having a bent free end and pivotally attached to said rod between its ends, a device adjustable manually in one 70 direction, a thermostat operable to hold said device in adjusted position and to release it under certain conditions of temperature, a flexible means connecting said device with said lever, a supplemental adjustable device, 75 and a flexible means connecting the latter device with the bent end of said lever.

In testimony whereof I affix my signature in presence of two witnesses.

ROBERT F. LINDSAY.
